GRILLEWORK FOR TREILLAGES, ROOM DIVIDERS OR THE LIKE

Robert F. Seery, Louisville, Ky., assignor to Julius Blum & Co., Inc., Carlstadt, N.J., a corporation of New York

Filed Nov. 10, 1961, Ser. No. 67,475

Term of patent 14 years

(Cl. D54—2)

FIG. 1

FIG. 2

FIG. 4

FIG. 3

FIG. 1 is an elevational view of a grillework for treillages, room dividers or the like, showing my new design, it being understood that the design unit shown has this form throughout;

FIG. 2 is an enlarged longitudinal, cross-sectional view taken on line 2—2 of FIG. 1;

FIG. 3 is an enlarged transverse sectional view taken on line 3—3 of FIG. 1; and

FIG. 4 is an enlarged transverse sectional view taken on line 4—4 of FIG. 1.

I claim:

The ornamental design for grillework for treillages, room dividers or the like, substantially as shown and described.
